UNITED STATES PATENT OFFICE

HENRY L. F. TREBERT, OF CANANDAIGUA, NEW YORK

INTERNAL-COMBUSTION ENGINE HAVING OSCILLATING PISTONS

Application filed September 29, 1927. Serial No. 222,721.

The object of this invention is to provide a new and improved form of an internal combustion engine having oscillating pistons of light weight and large horse power.

Another object of the invention is to simplify the packing of the joints between the moving and stationary parts of the engine.

Another object of the invention is to provide for the cooling of the piston and the stationary parts of the engine.

These and other objects of the invention will be illustrated in the drawings, described in the specification and pointed out in the claims at the end thereof.

In the drawings:

Figure 1 is a vertical transverse section through the engine.

Figure 2 is a vertical longitudinal section.

Figure 3 is a perspective view of one of the oscillating pistons and one of the compression heads.

Figure 4 is a longitudinal section through the piston on the line 4x, 4x of Figure 3 showing the channels through which the air circulates through the piston.

Figure 5 is an enlarged horizontal sectional view of one of the compression heads.

Figure 6 is a detail view of the eccentric packing ring on one of the cylinder heads.

Figure 7 is a section through the piston and hub on the line 7x, 7x of Figure 4.

Figure 8 is a section through the piston and the hub on the line 8x, 8x of Figure 4.

Figure 9 shows a modified form of the cylinder made with two radii.

In the drawings like reference numerals indicate like parts.

In the drawings reference numeral 1 indicates the casing of the engine which is made all in one casting and has provision therein for four cylinders spaced 90 degrees apart. The centers of these are placed equally distant from the drive shaft 6 of the engine.

These cylinders are indicated by the reference numerals 2, 3, 4 and 5. In the center of the engine casing is provided the drive shaft 6 which is preferably tubular in form to cut down the weight thereof. On the

opposed crank, the two wrist pins 8 and 9 of which are placed 180 degrees from each other, and are connected by the throws 10, 11 and 12 of the crank all of which parts are made in a single forging with the shaft 55 6. On the wrist pin 8 are pivoted the two connecting rods 13 and 14 and on the wrist pin 9 are pivoted the two connecting rods 15 and 16 by which connecting rods the crank and the shaft 6 are rotated. The 60 shaft 6 is mounted to rotate in an ordinary Babbitt bushing 17—A provided in the journal 17 which journal is cast integral with the frame. A roller bearing may be used instead. 65

Each of the cylinders is provided with heads 18 and 19 fastened on the opposite ends thereof by studs and nuts. The heads make a tight joint with the cylinder. The head and cylinder are shown in full line 70 on the outside at the lower right hand corner of Figure 2 and the head and cylinder are shown in section at the upper right hand corner of Figure 2.

A hollow shaft 20 is mounted to oscillate 75 in each of the cylinders. On each of these shafts a crank 21 is provided on which is pivoted the connecting rod through which the power thrust is communicated from the piston to the shaft 6. In each of the cylinders is mounted an oscillating piston having the two piston heads 22 and 23 on opposite sides of the hub 24, the piston heads being cast integral with the hub, the hub being keyed to the shaft 20 by the dovetailed joint 80 25 shown at the center. The hub 24 is recessed with two sets of ports as indicated at 26 and 27, the ports being spaced about 90 degrees between the centers thereof.

In each cylinder there are two sets of 90 compression heads 28 and 29 located on opposite sides of the cylinder. Below this compression head in each cylinder oscillates the piston head 23 and above the compression head oscillates the piston head 22. The mixture is drawn into the chamber in the lower part of each of the cylinders by the piston head 23 and is driven by the piston head 23 into the chamber 95 in the upper part of the cylinder as shown 100

at the top of Fig. 1 and is there compressed by the oscillating piston head 22 on both sides thereof and fired. The operation of the engine is substantially the same as the operation of the ordinary two cycle engine with this addition, that the mixture is compressed and fired alternately on both sides of the piston head 22.

As the piston head 23 oscillates to the right as shown at the top of Fig. 1 port 26 moves away from the compression head 28 and the hub 24 makes a tight joint with the inner wall 30 connecting the stationary walls of the compression head so that no gas can pass from one chamber into the other. At the same time the port 27 moves into operating position with reference to the curved stationary wall 31 of the compression head 29 on the opposite side of the cylinder. As the piston head 23 moves toward the head 29 it compresses the charge against the wall 33 which charge has previously been taken in through the port 36. This charge passes through the port 27 and into the upper chamber. By this time the piston head 22 has moved past the exhaust port 37 and the products of the explosion are free to pass out and the exhausting or scavenging of them is assisted by the flow of the fresh gases into the upper chamber through the port 27, as that gas is compressed by the piston head 23. While the piston head 23 is swinging to the right it is sucking into the lower chamber a fresh charge through the port 36 on the left of the piston head which charge is compressed when the piston oscillates in the opposite direction, which it does due to the fact that the gases have been compressed on the left of the piston head 22 and are fired at this moment causing an explosion which drives the piston head 22 to the right causing that piston head to drive out most of the remaining burnt gases and after it has passed the port 37 causing the compression of the fresh gases preliminary to firing the charge on the right hand side of the piston head 22. In this way the piston heads 22 and 23 are oscillated forward and back drawing fresh charges into the lower chamber on each side of the piston head 23 in turn and compressing such charges and causing the charges to flow into the upper chamber alternately on both sides of the piston head 22 by which piston head the charges are compressed and then fired driving the piston head 22 and generating the power that causes the oscillation of the piston and the crank which in turn drives the connecting rod. In this way the four cylinders drive the four pistons, their cranks and connecting rods and cause the rotation of the shaft 6 by the series of impulses thereon which impulses are communicated from two different cylinders at every 90 degrees of

the rotation of the shaft 6. There will be therefore, one explosion on each side of the piston head 22 or two explosions in each cylinder for each revolution of the shaft 6 and the explosions in the cylinders that are placed opposite to each other will occur at the same time.

The cylinders are air cooled and are provided on the outside thereof with a large number of fins as shown in the drawing. The piston heads 22 and 23 and the hub 24 are also air cooled and for this purpose are made hollow and on the inside thereof are provided with radiating fins and partitions 40 which are integral therewith. These fins extend around the hub connecting it with the sleeve and also extend up into the piston head and form pockets that are closed except for the openings in the sleeve and the shaft. Fins 41 are also provided on the sleeve which are staggered with the fins 40 connected to the hub. The fins 41 stop short of the hub and thus divide the pockets formed by the fins 40 in two parts. As shown at the top of Fig. 2 and Fig. 4, a blast of air is caused to pass through the hollow shaft 20 and this air blast passes through the ports 42 in the shaft 20 and sleeve into the hub, and the air is caused to circulate through the hub and out through the pockets of the piston, the air passing on one side of the fins 41 to the outer end of the piston pockets and then back on the other side of the fins 41 into the hub as shown in Figures 4 and 7. As appears from Figure 7, the air can divide and pass the short way around into the piston head 22 and the long way around into the piston head 23. It will be understood that the piston head 22 is exposed to the explosions and will therefore be hot while the piston head 23 is not exposed to the explosions and will, therefore, be comparatively cool, and for this reason the piston head 22 should receive, and does receive the most air for cooling. It will also be understood that water can be used for cooling the piston instead of air. The air passes out through the ports 44 and escapes through the shaft 20 on the other side of the partition 43.

The compression heads 28 and 29 with the walls 32, 33, 34 and 35 therein are each made of a separate casting which is bolted into the cylinder and each is provided with suitable flanges with holes therein for this purpose. These flanges are provided on both ends so that the compression heads can be bolted to the cylinder heads on both ends of the cylinder, and in the cylinder and compression head a key way 50 is provided in which a suitable key is set for the purpose of holding the compression head firmly and correctly in position. These compression heads are made hollow and are provided with small radiating fins 51 set on webs that

connect the opposite walls 32 and 34, the whole structure being made in a single casting. It will also be understood that the cylinder heads are cut away above and below the interior of the compression heads so as to permit the free circulation of air through the hollow part of the compression head. The walls 30 and 31 of the compression heads are provided with grooves in which packing bars or strips are provided which are pressed out by flexible flat springs to make a gas tight joint with the hub. The ends and sides of the piston heads 22 and 23 are grooved in the same way and are provided with similar packing bars held in place with similar springs.

As shown in Figure 2 the crank case or housing 60 is made in two parts 61 and 62 which are joined together with flanges 63 and 64 and are suitably bolted together. A bearing 65 is provided in the housing for supporting the shaft 6. Each of the hollow shafts 20 pass through the crank case and is supported by a journal bearing 66 to the outer end of which connects an air duct 67 into which duct the hot air is discharged from the shaft 20. The air passes outward through this duct and at the upper end of the duct the exhaust manifold 68 discharges through the opening 69. The exhaust from the manifold 68 causes a suction which draws the air from the shaft 20 after it. The duct 67 is enlarged to surround the end of the manifold 68 with a clearance, that is well adapted to draw the air up through the duct 67 and the shaft 20 by the blast of the exhaust manifold 68. The manifold 68 is also adapted to act as a muffler to lessen the noise of the exhaust and cold air is forced through the manifold by a fan or propeller that is suitably placed in front of the engine.

At 70 I have indicated the intake manifold through which the mixture is drawn from the carburetor. This manifold leads direct to a chamber 71 surrounding the journal bearing 17 from which the mixture is distributed direct to the intake port of the four cylinders. The mixture is normally cold and serves the extra purpose of keeping the journal bearing 17 and the power shaft 6 cool.

On the two opposite sides of the explosion chamber are provided the openings 73 for the spark plugs 74 which are used to fire the charges. The firing of the charges is timed by any of the well known timing devices any of which may be used or adapted to this engine.

It will also be understood that while the parts 2, 3 etc. are shown as cylinders, the cylindrical wall of the one chamber can be made with a different radius from the cylindrical wall of the other chamber and the length of the piston heads will be changed

to correspond, to get the correct ratio of the charge, compression and expansion. The piston heads can be made of different widths from each other to vary the space left in the chambers in which they operate.

In Figures 2 and 6 I have shown a packing ring in each cylinder head which bears against the hub and makes a tight joint between the cylinder head and the hub. This packing ring is indicated by the numeral 80 and is shown eccentric to the hub in Figure 6. The packing ring is placed eccentric so that it will not wear in a groove at the end of the hub.

I claim:

1. An engine having a cylinder with a piston mounted to oscillate therein, said piston having a hub and two piston heads thereon placed opposite each other, stationary compression heads in said cylinder which with said hub divides the cylinder into two chambers, in each of which one of said piston heads is adapted to oscillate, an intake port located centrally in the one chamber and an exhaust located centrally in the other chamber, an intake and an exhaust port located in the periphery of the cylinder on opposite sides thereof and midway between the stationary compression heads.

2. An engine having a cylinder with a piston mounted to oscillate therein, said piston having a hub and two piston heads thereon placed opposite each other, stationary compression heads in said cylinder which with said hub divides the cylinder into two chambers, in each of which one of said piston heads is adapted to oscillate, said piston being adapted to draw a charge into one of said chambers and drive it into the other chamber past one of said stationary heads, means for exploding it in the last named chamber to drive the piston, an intake and an exhaust port located in the periphery of the cylinder on opposite sides thereof and midway between the stationary compression heads.

3. An engine having a cylinder with a piston mounted to oscillate therein, said piston having a hub and two piston heads thereon placed opposite each other, stationary compression heads in said cylinder which with said hub divides the cylinder into two chambers, in each of which one of said piston heads is adapted to oscillate, said piston being adapted to draw a charge into one of said chambers and drive it into the other chamber past one of said stationary heads, means for exploding it in the last named chamber to drive the piston, a shaft with which said piston oscillates, a crank on said shaft, a connecting rod driven thereby, a crank and shaft rotated thereby, an intake and an exhaust port located in the periphery of the cylinder on opposite

sides thereof and midway between the stationary compression heads.

4. An engine having a cylinder, a piston mounted to oscillate therein, said piston having a large hub extending the length thereof and a piston head on each side thereof extending radially therefrom, ports recessed in said hub and extending partly around said hub, both of said ports being adjacent to one of said piston heads, the balance of said hub being free from ports.

5. An engine having a cylinder, a piston mounted to oscillate therein, said piston having a large hub extending the length thereof and a piston head on each side thereof extending radially therefrom, ports recessed in said hub and extending partly around said hub; a compression head on each side of said cylinder and making close contact with said hub, said ports being adapted to connect with the cylinder on opposite sides of said compression head in a given position of the piston.

6. An engine having a cylinder, a piston mounted to oscillate therein, said piston having a hub, a head at each end of the cylinder, a circular packing ring mounted adjacent to each hub and adapted to press against the end of the hub to seal the joint, said packing ring being placed eccentrically to the center of the hub.

7. An internal combustion engine having a cylinder with two segmental chambers therein placed opposite to each other and separated from each other by stationary heads therein, a piston adapted to oscillate in said cylinder and in said chambers, an intake port in one chamber and an exhaust port in the other chamber, said ports being located opposite each other in said cylinder and in the periphery thereof.

In testimony whereof I affix my signature.

HENRY L. F. TREBERT.
